(57) **CLAIM**

The ornamental design for a sock, as shown and described.

DESCRIPTION

1. Sock
- 1.1 : Front
- 1.2 : Back
- 1.3 : Left
- 1.4 : Right
- 1.5 : Top
- 1.6 : Bottom
- 1.7 : Enlarged

The subject article is a sock having a heel portion that is provided with gore lines; the sock is designed to fit the back of the heel at the higher position when it is worn; the white-marked parts are not coming into the scope of the industrial design (disclaimer).
